UNITED STATES PATENT OFFICE

2,486,571

BUFFING MECHANISM

Roland J. Olander, Chicago, Ill., assignor to W. H. Miner, Inc., Chicago, Ill., a corporation of Delaware

Application August 25, 1945, Serial No. 612,615

3 Claims. (Cl. 213—222)

1

This invention relates to improvements in buffing mechanisms for railway cars.

One object of the invention is to provide a buffing mechanism for railway cars including a buffer face plate and spring resisted side stems for supporting the face plate from the usual end platform of the car, wherein the buffer side stems are readily removable without disturbing the other parts of the mechanism by so constructing the parts that the side stems and their associated springs may be withdrawn through the rear guide brackets for the stems.

Other objects of the invention will more clearly appear from the description and claims hereinafter following.

In the drawing forming a part of this specification, Figure 1 is a broken, top plan view of the end platform and buffer face plate of a railway car, illustrating my improvements in connection therewith, the end platform being partly broken away to show the parts beneath the same, the rear guide bracket for the buffer stem and the buffer side stem spring being shown in horizontal section. Figure 2 is a horizontal, longitudinal sectional view taken through the rear guide bracket of the buffer mechanism and showing the rear end portion of the buffer side stem in plan. Figure 3 is a front elevational view of the two-part bearing sleeve for the buffer side stem, looking from left to right in Figure 2.

In said drawing, 10 indicates the usual end platform of a passenger car and 11, the buffer face plate. The end platform has a pocket 12 which accommodates a usual friction shock absorber, indicated by 13, but not shown in detail, which cooperates with a sliding buffer center stem 14, which bears at its front end on the face plate 11. At opposite sides of the center stem, the end platform 10 is provided with the usual guides 15—15 for the buffer side stems, the guide at one side only of the mechanism being shown in the drawing.

In carrying out my invention, I provide broadly a buffer side stem A at each side of the buffer center stem; a rear guide bracket B for each side stem A; a collar C on each side stem; a two-part bearing sleeve D within each rear bracket B; a buffer spring E associated with each buffer stem; and a retaining nut F at the end of each stem.

The side stem A is of the usual design, being pivotally connected at its front end to the buffer face plate in a well-known manner, the buffer face plate being provided with a bracket 16 to which the front end of the stem is attached by a

2

pivot pin 17. As is the usual practice, the front end portion of the stem A, which is indicated by 18, is of angular cross section and slidably guided in the guide 15. The rear portion of the stem, which is indicated by 19, is of cylindrical cross section, thus providing an abutment shoulder 20 for the collar C. The portion 19 of the side stem A is threaded at the rear end to receive the usual retaining nut F.

10 The rear bearing bracket is fixedly mounted on the end platform 10 in the usual manner and is provided with a tubular sleeve-like portion 21 of cylindrical form. The opening of the sleeve portion 21, which opening is indicated by 22, is of 15 relatively large diameter and has its longitudinal axis arranged lengthwise of the end platform and is in longitudinal alignment with the guide 15.

10 The collar C has a cylindrical spring centering 20 portion 23 and a laterally projecting, annular flange 24 at the forward end of the portion 23. The flange 24 is of lesser diameter than the opening 22 of the bracket B so that the collar may 25 pass freely through the opening of the bracket. The collar C is mounted on the portion 19 of the side stem, being freely slideable thereon. This 15 collar normally abuts the rear end of the guide 15 and the shoulder 20 of the side stem A.

20 The bearing sleeve D comprises two similar sections surrounding the rodlike rear portion 19 of the side stem A within the bracket B. The two sections of the sleeve D together form a substantially cylindrical, tubular member, which is split in half lengthwise. The sleeve D has an 35 outstanding, annular flange 25 at the forward end bearing on the front side of the tubular section 21 of the bearing bracket B. Forwardly of the flange, the sleeve D is provided with a forwardly projecting, cylindrical spring centering 40 portion 26, corresponding in diameter to the centering portion 23 of the collar C.

45 The buffer side stem spring E is of the type usually employed in connection with buffer side stems, being in the form of a helical coil surrounding the stem. The spring E bears at its front and rear ends respectively on the flange 24 of the collar C and the flange 25 of the two-part sleeve D. The projection 23 on the collar C and the projection 26 on the sleeve D, over 50 which the opposite ends of the spring are telescoped, hold the same centered.

The nut F, which is threaded on the rear end of the side stem A, bears on a washer 27 in shoudered engagement with the rear end of the guide

bracket B to limit forward or outward movement of the side stem.

In removing the side stem, the same is first detached from the face plate 11 by removing the pivot pin 17. The split bearing sleeve D is then pushed forwardly out of the bracket B against the resistance of the spring E until it is entirely clear of the bracket. The sections of the bearing sleeve D are then separated and removed. This leaves the opening of the bracket B clear for withdrawal of the side stem A, spring E, and collar C. All of these parts may be removed as a unit by pulling the side stem with the spring E and collar C thereon rearwardly through the opening 22 of the bearing bracket B.

In assembling the side stem with the other parts, a procedure substantially the reverse to that just described is followed.

I claim:

1. In a buffing mechanism, the combination with the end platform of a car; of a buffer face plate; a side stem for supporting said face plate from the end platform; a spring surrounding the rear end portion of said stem; a collar on said stem on which the front end of said spring bears; a rear supporting bracket for the side stem, said bracket having an opening therethrough of a size to permit withdrawal of the side stem, surrounding spring, and collar lengthwise therethrough; a longitudinally split, two-part removable bearing sleeve in which the rear end of the side stem is slidably guided, said sleeve being seated in and fitting the opening of said bracket with the parts thereof embracing said stem at opposite sides; and means for holding said sleeve against rearward movement in said bracket.

2. In a buffing mechanism, the combination with the end platform of a car; of a buffer face plate; a side stem for supporting said face plate from the end platform; a buffing spring surrounding the rear end portion of said stem and yieldingly resisting inward movement of said stem; a rear supporting bracket for the side stem, said bracket having an opening therethrough of a size to permit withdrawal of the side stem and sur-

35

40

45

rounding spring therethrough; and a longitudinally split, two-part, removable bearing sleeve in which the rear end of the side stem is slidably guided, said sleeve being seated in and fitting the opening of said bracket with the parts thereof embracing said stem, each of the parts of said sleeve having a flange at the front end thereof bearing on the front end of said bracket to hold said parts against rearward movement, said sleeve bearing at its front end on the rear end of said

5 10 15 20 25 30 35 40 45

spring.

3. In a buffing mechanism, the combination with the end platform of a car; of a buffer face plate; a side stem for supporting said face plate from the end platform; a collar on said stem having shouldered engagement with the stem to limit forward movement of the same on said stem; a spring surrounding said stem rearwardly of said collar; a rear supporting bracket for said side stem, said bracket having an opening therethrough, through which said stem projects, said opening being of a size to permit lengthwise withdrawal of the buffer stem therethrough with the surrounding spring and collar thereon; a two piece, lengthwise split, bearing sleeve within the opening of said bracket embracing said stem at opposite sides, each part of said sleeve having a flange at the forward end thereof bearing on the front end of said bracket, said spring bearing at opposite ends on the rear side of the collar and the front end of said sleeve; a nut on the rear end of said stem; and a washer interposed between said nut and the rear side of the bearing bracket.
